**SEALED CONNECTION FOR HEATING ELEMENTS
AND METHOD OF ASSEMBLING**Guy A. Josephine, Albion, Mich., assignor to McGraw-
Edison Company, Milwaukee, Wis., a corporation of
Delaware

Filed Apr. 14, 1960, Ser. No. 22,261

7 Claims. (Cl. 338—329)

This invention relates to a hermetically sealed connection for a housed heating element and to the method of assembling the connection and is particularly directed to a terminal connection made within an opening in a housing for a heating element through which the power supply lines are connected to the heating element.

Electric heating elements of the immersion type are inserted freely into contained liquids. At times the heating unit is thrust into the liquid beyond the power supply connection and it is important that the connection be hermetically sealed to prevent any leakage of electricity or power into the liquid in such an instance.

Immersion type heating elements are also employed to heat air which is very humid. A hermetic seal is then also necessary to prevent similar power loss.

Housed resistor electric heaters have been developed with the resistor heating element disposed within a metallic housing or sheath and embedded in a suitable electrically insulating and heat conducting refractory material to prevent shorting of the element. The refractory embedding material must be thoroughly dry and protected against any moisture in order to maintain and preserve the insulating and heat conducting characteristics of the refractory material which is conventionally employed. The housing is conventionally tubular shaped having one end open through which the heating element is interconnected to incoming power lines. The open end is then hermetically sealed to prevent liquid leakage through the opening and thereby prevent passage of electricity to the immersing liquid or contaminating of the refractory material.

Various rigid and compressed sealing members have been employed to close the opening about the power lead or supply line connections. Thus, vitreous material and similar rigid members have been disposed within the opening in attempts to seal the opening. Compressed rubber-like members have also been employed to establish a tight hermetic seal adjacent the opening. A particularly satisfactory sealed housing construction is disclosed in U.S. Patent No. 2,840,676 which issued June 24, 1958, wherein a suitable flowable material such as an epoxy resin is disposed immediately adjacent the inner surface of an outer cover or cap which is secured to the open end of the sheath or housing for the element to seal the end of the housing. The terminal means of the heating elements projects outwardly through the sealing material and the cover to establish connection to incoming power lines.

The present invention is directed to a particularly inexpensive construction for sealing the opening and completely encasing the connection and to the method of assembling the sealing members. The construction and method of the present invention are more particularly adapted to economical production of a commercial heater having a permanently sealed connection which is completely embedded within a suitable resilient flowable material.

Generally, the present invention includes a sheathed heating element having an opening through which a wire-like terminal connection is made. An insulating plug is supported within the sheathed housing and projects partly into the housing terminating in spaced relation to the re-

2

fractory embedding material. The insulating plug includes a plurality of openings to accommodate the power supply lines and to allow introduction of a sealant through the plug and into the sheath and the openings in the plug after assembly of the plug over the sheath opening. Thus, with a conventional dual-conductor power line, a pair of openings is provided one for each of the incoming power lines. A third opening is provided through which the sealant is inserted into the sheath. The sealant flows into the cavity adjacent the sheath opening and then flows backwardly and outwardly through the power lead connection openings to completely fill the cavity in the housing and the openings in the plug.

Although the third opening may be eliminated and the sealant poured directly through the lead-in openings, the third pouring openings provide a very rapid and inexpensive method of introducing the sealant into the assembly to positively fill all voids. Consequently, this provides a very economical and practical construction or method of assembling.

The sealant serves to hermetically close the lead-in opening and further bonds to the connection of the power supply lines and the terminal means of the heating element to physically support the electrical connection.

The initial assembly is made by assembling the plug onto the power lines with power lines projecting outwardly from the plug. Connection of the terminal means and the incoming power lines is completed. After the connection is made, the plug is slipped down over the connection and into the lead-in opening with the inner end projecting partly into the housing. The sealant material is then inserted through the special filling opening to completely fill the cavity and hermetically seal the opening upon setting of the material. The use of the plug reduces the quantity of the sealant which must be employed. This is important because the sealant is normally the more expensive product employed in the sealing of the opening. This sealant provides the necessary hermetic seal and insulation at the lead-in opening as well as physically supporting the electrical connection of the power supply line to the terminal means.

The present invention provides a very simple and rapidly assembled sealed terminal for electric immersion heaters and the like.

The drawing furnished herewith illustrates the best mode presently contemplated for carrying out the invention.

In the drawing:

FIG. 1 is a perspective elevational view of an immersion type heater constructed in accordance with the present invention;

FIG. 2 is an enlarged vertical section through the heater shown in FIG. 1 illustrating the terminal connections in accordance with the present invention;

FIG. 3 is a vertical section through the heater of FIG. 1 taken on a plane at 90° to the vertical section of FIG. 2; and

FIG. 4 is a view of the heater 1 during the process of assembly of the illustrated embodiment of the invention.

Referring to the drawing and particularly to FIGS. 1 and 2, an electric heater of the immersion variety is shown generally including a heating unit 1 which is shown as a finned assembly for purposes of illustration only. The heating unit 1 is connected to a pair of power leads 2 by a sealed terminal connection 3 which is constructed in accordance with the present invention.

The heating unit 1 includes an outer tubular sheath 4 of a suitable material. Aluminum and the like are very satisfactory. One end of the sheath 4 is closed by an integral end wall 5 while the opposite end of the sheath 4 is opened to receive a generally U-shaped heating ele-

ment 6, which is supported within a cylindrical ceramic core 7.

The heating element 6 is shown in outline only. In actual practice, the element will normally take the shape of a double spiral coil which extends axially through spaced openings in core 7.

The core 7 terminates within the sheath 4 and carries a pair of embedded terminal pins 8 connected to the adjacent ends of the U-shaped heating element 6. The pins 8 project axially outwardly from the core 7 and through the open end of sheath 4 for connection to power leads 2.

A suitable electrical insulating refractory material 9 such as magnesium oxide or the like completely fills the space between the sheath 4, the ceramic core 7 and the core openings accommodating the heating element 6 in accordance with known construction. Material 9 also covers the end of the core 7 adjacent the pins 8 for a predetermined depth substantially less than the depth of the cavity or chamber between the end of the core 7 and the outer edge of the sheath 4.

A spiral fin 10 is integrally formed with the sheath 4 in the illustrated embodiment to increase the heat dissipating area of the heating unit 1, although the fin may be eliminated within the present invention. A separate end fin 11 is secured to the outer end of the sheath 4 as by welding or the like. The end fin 11 constitutes a name plate and carries various indicia 12 including the recommended voltage of the incoming power leads 2, the wattage of the unit, the manufacturer and the like.

The leads 2, constituting the power supply lines, are similar in construction and in connection to the pair of terminal pins 8 and consequently only a single description is here given. Corresponding numbers in the two connections identify corresponding elements.

The lead 2 is a standard commercial product consisting of a stranded cable 13 which is enclosed within a suitable insulating cover 14 of flexible rubber or synthetic material such as neoprene. The end of the cover 14 is stripped back behind the end of the stranded cable 13 as at 15 to receive a connector clip 16 which is adapted to interconnect the incoming end of the lead 2 to a corresponding terminal pin 8; generally exteriorly of the outer end of the sheath 4 in the illustrated embodiment of the invention.

The connector clip 16 is generally of a standard type construction and includes an outer split band 17 which is physically clamped about the stripped end 15 of the lead 2. An intermediate split band 18 accommodates the outer end of a terminal pin 8 and the stripped end 15. The split band 18 is clamped about the corresponding end of pin 8 and stranded cable 13. Solder or the like 19 may be employed at split band 18 to insure good electrical connection of the pin 8 to the stranded cable 13. The connector clip 16 also includes an inner split band 20 which is clamped about the outer end 21 of terminal pin 8 to physically interconnect and support the connection of the pin 8 to the connector clip 16.

A tubular plug 22 encloses the connector clip 16 and the adjacent ends of lead 2 and pin 8.

The plug 22 is formed of a suitable insulating material and is preferably formed of nylon or the like. Plug 22 is generally a cylindrical member having an outer diameter generally corresponding to the diameter of the lead-in opening in the sheath 4. An intermediate flange 23 is integrally formed on the plug 22 and is adapted to seat upon the adjacent end fin 11 to properly locate the plug 22 with the innermost end of the plug extending into the sheath 4 and terminating in spaced relation to the refractory material 9. The inner end of the plug 22 is tapered as at 24 and the sheath 4 is correspondingly tapered for a portion of the length of the inner end of tubular plug 22 to establish a slight annular void 25 between the innermost end of the plug 22 and the adjacent surface of the sheath 4. The plug 22 includes a pair of

lead-in openings 26 having a diameter slightly greater than the outer diameter of the insulated power leads 2. The lead-in openings 26 accommodate the connector clips 16 and the adjacent ends of the terminal pins 8 and the insulated power leads 2. In particular, the ends of power leads 2 are inserted into the lead-in openings 26 with a portion of the insulating cover 14 within the lead-in openings.

A sealant 27 completely fills all of the voids within the terminal cavity in the sheath 4 adjacent the open end of the sheath as well as all of the openings in the plug 22. The sealant is any suitable plastic-like material which sets to a relatively hardened state and which will bond to the adjoining surfaces to hermetically close the open end of the sheath 4. The sealant 27 fills the annular space or void 25 between the inner end of the plug 22 and the sheath 4 to insure a firm and positive locking of the plug 21 within the opening and establish an excellent seal between the adjoining surface of plug 22 and sheath 4.

The sealant 26 is preferably a thermo-setting plastic such as an epoxy resin which can be inserted as a liquid with hardening and curing agents to flow into the sheath 4 and plug 22. Epoxy resins and the like also bond to the adjoining surfaces upon setting to establish a positive sealing of the lead-in opening.

Referring particularly to FIG. 3, the plug 22 includes a filling opening or passage 28 extending axially through the plug 22 parallel to and spaced from the lead-in openings 26. An epoxy resin sealant 27 or other suitable material is inserted through passage 28 to completely fill the cavity within the outer end of the sheath 4 including the void between the inner end of the plug 22 and the sheath 4. The air exhausts outwardly through the lead-in openings 26. The sealant 27 flows outwardly through the lead-in openings 26 to completely encase the terminal pins 8, the connector clips 16 and the adjacent ends of the leads 2. Upon curing, the sealant 27 hermetically closes the lead-in opening to positively prevent contamination of the refractory material 9 or leakage of electricity from the heating unit into the immersing liquid, not shown. The sealant 27 also bonds to the adjacent surfaces to physically support the plug 22 as well as the physical connection of the cable 2 to the terminal pins 8.

Referring particularly to FIG. 4, the illustrated embodiment of the invention is initially assembled in the following manner.

Plug 22 is assembled with the leads 2 projecting outwardly through the axial lead-in openings 26. The terminal pins 8 and the stripped ends 15 of leads 2 are crimped and, if desired, soft soldered to the connector clip 16, as previously described. The plug 22 is then moved downwardly along the leads 2 and into the open end of the sheath 4 with the intermediate radial flange 23 seated against the end fin 11. The cooperating tapered portion 24 of plug 22 and the taper in the outer end of sheath 4 facilitate the assembly of the plug 22 with the sheath 4. The sealant 27 is then inserted through the filling passage 28 until the cavity within the sheath 4 is filled and the sealant flows outwardly through the axial lead-in openings 26 to completely encase the interconnection of the cable 2 to the terminal pins 8. The sealant is then set to establish the hermetic enclosure and to support the plug 22.

Although illustrated in connection with a U-shaped heating element, the terminal connection of the present invention is equally applicable to a straight-through construction wherein the lead-in connections are made at opposite ends of the unit, to a conventional cartridge type heater or to any other heating unit having a lead-in opening or openings to be hermetically sealed.

The present invention provides a positive and excellent hermetic closure at the lead-in opening in an economical and simple manner without the necessity of unsightly sealing accessories.

Various modes of carrying out the invention are contemplated as within the scope of the following claims par-

ticularly pointing out and distinctly claiming the subject matter which is regarded as the invention.

I claim:

1. In an electrical heating assembly having a heating element having terminal pins connected to power leads, a housing having a lead-in opening and enclosing the heating elements with the terminal pins projecting outwardly through the opening, an electrically insulating and heat conducting medium filling the housing about the element and defining a terminal cavity adjacent the opening, a plug member mounted within the opening with at least a portion of the surface of the plug in direct engagement with an interior portion of the housing and terminating in spaced relation to the medium, said plug having axial lead openings, connectors disposed within said axial lead openings and joining the power leads and the terminal pins within said axial lead openings, said plug having an assembly opening spaced from said lead openings and extending through the plug from an exterior portion to the terminal cavity with the plug mounted within the lead-in opening, and a thermo setting plastic material filling the terminal cavity and the lead openings and the assembly opening in the plug to hermetically seal the lead-in opening of the housing and bonded to adjacent surfaces to lock the plug within the opening and to mechanically support the terminal pins and power leads to the connector.

2. In an electrical heating assembly including a heating element with terminal pins connected to power leads, a tubular housing having at least one open end and enclosing the heating elements with the terminal pins projecting through the opening, an insulating medium filling the housing about the element and defining a terminal cavity adjacent the open end, a tubular plug member mounted within the opening and terminating in spaced relation to the insulating medium, said plug having axial lead openings accommodating the power leads and the terminal pins, connectors disposed within the axial openings in said plug and having end clamps secured to adjacent end portions of the power leads and the pins and having an intermediate soldered clamp joining the power leads and the terminal pins, said plug member including an axial assembly opening extending therethrough, and a thermo setting plastic material filling the terminal cavity and the lead openings and the assembly opening in the plug to hermetically seal the end of the housing.

3. A terminal connection for a housed heating element having wire-like terminal means passing outwardly through an open end of a tubular housing for connection to insulated power supply lines, which comprises connecting means joining the power supply lines to the terminal means, a tubular closure plug mounted in the open end of the housing and having an outer radial flange seated on the end of the housing to locate the housing, said plug having individual axial lead openings within which the connected terminal means and the supply line are located, said axial lead openings being larger than the incoming power supply lines to freely receive the insulated lines, the outer surface of the end of the plug within the housing being tapered to establish an annular space therebetween, said plug member including an axial assembly opening extending therethrough, and a potting compound filling the open-end of the housing and the axial lead openings and the axial assembly opening of the closure plug to hermetically seal the lead-in opening and lock the plug to the housing.

4. In an electrical heating assembly having a heating element with terminal pins connected to power leads, a housing having an open end and enclosing the heating elements with the terminal pins projecting through the open end, heat dissipating fins secured to the outer circumference of the housing and having an end fin extending perpendicular to the axis of the housing, said end fin constituting a nameplate to carry information relating to the heating assembly, an insulating medium filling the housing

about the element and defining a terminal cavity adjacent the opening, a tubular plug member mounted within the opening and terminating in spaced relation to the insulating medium and having an intermediate flange seated on the end fin to locate the plug, said plug having axial power lead openings individually accommodating the power leads and the terminal pins, a third axial opening extending in spaced parallel relation to said power lead openings, connectors joining the connected power leads and the terminal pins within the power lead openings, the outer surface of the plug within the housing being tapered inwardly to define an annular space therebetween, the outer portion of the inner surface of the housing adjacent the plug being correspondingly tapered, and a thermo setting material filling the terminal cavity and the axial openings in the plug to hermetically seal the end of the housing.

5. In a method of sealing a terminal connection of a housed heating element having wire-like terminal means extended through a lead-in opening in the housing and connected to power supply lines, assembling a closure plug having a filling opening and lead openings with the terminal ends of the supply lines so that the supply lines extend through said lead openings, connecting the supply lines to the terminal means, moving the closure plug along the supply lines and into the lead-in opening with the connection of the supply lines and terminal means being located within the lead openings, thereafter filling the plug and housing including the lead openings and the filling opening through the filling opening with a curable thermo-setting plastic and curing said thermosetting plastic to hermetically seal the lead-in opening.

6. In a method of sealing a terminal connection of a housed heating element having wire-like terminal means extended through a lead-in opening in the housing and connected to power supply lines, assembling a closure plug having lead-in openings with the terminal ends of the supply lines and having a filling opening generally parallel to the lead-in openings, connecting the supply lines to the terminal means, moving the closure plug along the supply lines and into the lead-in opening, and introducing a potting compound into the housing adjacent the plug through the filling opening to completely fill the plug and housing adjacent the opening with the potting compound and hermetically seal the lead-in opening.

7. A terminal connection for a housed heating element having terminal means extended through a lead-in opening in the housing for connection to insulated power supply lines, which comprises connecting means joining the power supply lines to the terminal means, a closure plug mounted in said lead-in opening and having at least one longitudinal lead opening within which the connected terminal means and the supply lines are located, said longitudinal lead opening being larger than the incoming power supply lines to freely receive the insulated lines, said closure plug including a longitudinal potting opening spaced from said lead opening, and a potting medium filling the housing adjacent the lead-in opening and the longitudinal openings of the closure plug and bonded to the adjacent surfaces to hermetically seal the lead-in opening and lock the plug within the opening.
